UNITED STATES PATENT OFFICE.

WALTER H. COATES, OF NATHALIE, VIRGINIA.

RAILROAD-TRACK CLEARER.

1,162,338.

Specification of Letters Patent. Patented Nov. 30, 1915.

Application filed February 15, 1915. Serial No. 8,324.

To all whom it may concern:

Be it known that I, WALTER H. COATES, a citizen of the United States, residing at Nathalie, in the county of Halifax and State 5 of Virginia, have invented certain new and useful Improvements in Railroad-Track Clearers; and I do hereby declare the following to be a full, clear, and exact description of the invention, such as will enable 10 others skilled in the art to which it appertains to make and use the same.

This invention relates to track clearers, the principal object of the same being to provide a device of simple construction to 15 be attached to the pilot beam of a locomotive, and to be operated by a lever or connection within the cab of the locomotive for raising and lowering a clearer blade or 20 plate to a position to remove obstructions lying upon the track rails.

The foregoing and other objects may be attained by means of the construction illustrated in the accompanying drawings, in which—

25 Figure 1 is a front elevation of a track clearer made in accordance with this invention and connected to the pilot beam of a cow-catcher on a locomotive, Fig. 2 is a perspective view of the track clearer disconnected from the locomotive, Fig. 3 is a side elevation of the track clearer in position for use, Fig. 4 is a detail front elevation of one 30 of the clearer blades and the guide therefor, the lower end of said blade and the ends 35 of the guides being shown broken away, and Fig. 5 is an enlarged horizontal sectional view of one of the clearer blades and its guide member.

Referring to the drawings, the numeral 1 40 designates the pilot-beam of a locomotive and 2 is the cow-catcher. Journaled in bearings 3 on the upper side of the pilot-beam 1 is a rock shaft 4, and extending at right angles and secured to said rock shaft 45 4 are arms 5, said arms being in vertical alinement with the track rails α .

The clearer blades 6 are mounted in vertical guide members each consisting of a back portion 7 provided with a slot 8, two 50 spacing members at the side indicated by the numerals 9 and a front plate 11 secured by bolts 12 to the spacing strips 9. The guide members are connected to the cross bar 1 by fastening plates 13, said guide members being 55 in vertical alinement with the track rails α .

Projecting outward from the clearer blade

6 are rods 14, said rods being in vertical alinement with the rods 5, and chains or other flexible connections 15 are connected to the outer ends of the rods 5 and 14. A 60 stop pin 16 is secured to each clearer blade 6 to limit the downward movement of said clearer blades, and these pins project sufficiently through the slot 8 to limit the upward movement of said clearer blades. 65

Connected to the rock shaft 4 at one end thereof is an arm 17, and pivoted to the upper end of this arm is a connecting rod 18 which leads to the cab and is provided with suitable means within reach of the engineer 70 for operating the track clearer by rocking the shaft 4 and raising and lowering the clearer blades 6.

From the foregoing it will be obvious that when the clearer blades 6 are in their lowermost positions, the lower ends of said clearer blades are disposed about one-fourth of an inch from the tread surface of the rails α , and will clear the rails of any obstructions which would be liable to derail the train, 80 such as bolts, and other obstructions of similar character. The clearer blade 6 may be raised as the train nears a station, in order that signal torpedoes may not be swept off the rails. 85

Various changes may be made in the details of construction without departing from the spirit and scope of the invention as defined in the claims.

What is claimed is:—

1. A track clearer comprising a bearing secured to the pilot beam of a locomotive, a rock shaft mounted in said bearings, rods extending out from said shaft at points immediately above the track rails, back guide plates, short front guide plates secured at their lower ends to the back of the cow-catcher, spacing bars between said plates and being secured to the pilot beam, bolt connecting said plates and spacing bars, said plates being in vertical alinement with the track rails, clearer blades slidably mounted between said plates, rods extending out from said blades, flexible connections between said clearer blade rods and rock shaft rods, and means for rocking said shaft and thereby raising or lowering said clearer blade. 95

2. A track clearer comprising a bearing secured to the pilot beam of a locomotive, a rock shaft mounted in said bearings, rods extending out from said shaft at points immediately above the track rails, back guide 100 plates, short front guide plates secured at their lower ends to the back of the cow-catcher, spacing bars between said plates and being secured to the pilot beam, bolt connecting said plates and spacing bars, said plates being in vertical alinement with the track rails, clearer blades slidably mounted between said plates, rods extending out from said blades, flexible connections between said clearer blade rods and rock shaft rods, and means for rocking said shaft and thereby raising or lowering said clearer blade. 105

110

plates, short front guide plates secured at their lower ends to the back of the cow-catcher, spacing bars between said plates and being secured to the pilot beam, bolt 5 connecting said plates and spacing bars, said plates being in vertical alinement with the track rails, clearer blades slidably mounted between said plates, rods extending out from said blades, flexible connections between said clearer blade rods and rock shaft rods and means for rocking said shaft and thereby raising or lowering said clearer 10

blade, said back guide plates each having a slot, a pin secured to each of said clearer blades and extending through said slots 15 thereby limiting the movement of said clearer blades.

In testimony whereof I affix my signature in presence of two witnesses.

WALTER H. COATES.
